UNITED STATES PATENT OFFICE.

STEPHEN A. COUSE, OF ENDICOTT, NEW YORK.

COUNTER ATTACHMENT FOR TYPEWRITERS, ETC.

Application filed November 17, 1922. Serial No. 601,614.

To all whom it may concern:

Be it known that I, STEPHEN A. COUSE, a citizen of the United States, residing at Endicott, in the county of Broome and State 5 of New York, have invented certain new and useful Improvements in Counter Attachments for Typewriters, Etc.; and I hereby declare that the following is a full, clear, and exact description thereof, reference being had to the accompanying drawings, which form part of this specification.

This invention is a novel word-counter attachment for bookkeeping machines, typewriters, and the like. The object of the invention is to provide novel means for operatively connecting a counter (such as a "Veeder cyclometer") to a machine, such as an Elliott-Fisher machine, or a typewriter, whereby the counter will be actuated one 10 unit for each effective operation of the machine.

The invention includes a counter and a reciprocable rod having one end connected to a suitable movable part of the machine, and 15 the other end thereof mounted in a suitable guide, and a spring finger on said rod adapted to engage a ratchet wheel mounted on the counter shaft, so that at each movement of said part of the machine, resulting from the 20 proper depression of a key of the machine, said spring finger will be caused to engage and turn the ratchet wheel one tooth, and after the ratchet wheel has been turned a distance of one tooth, the spring finger will 25 disengage the ratchet and ride on the teeth thereof, thereby preventing the ratchet wheel being turned more than one tooth for 30 each proper movement of said part of the machine.

I will explain the invention with reference to the accompanying drawings to enable others to adopt and use the same, and summarize in the claims the novel features of construction, and novel combinations of 35 parts, for which protection is desired.

In the drawings:

Fig. 1 is a side view of the attachment as applied to an "Elliott-Fisher" machine.

Fig. 2 is an enlarged sectional view on the line 2—2 Fig. 1, looking down.

Fig. 3 is an enlarged section on the line 3—3 Fig. 1 looking up.

Fig. 4 is a perspective view of the counter support and ratchet wheel housing detached.

Fig. 5 is a detail view of a modified form of actuating rod.

The novel counter attachment comprises a counter V (preferably a Veeder cyclometer, as shown in Patent #548,482,) a ratchet wheel 1 attached to the counter actuating shaft; a reciprocable rod 3 operated by a suitable part of the machine to which the attachment is connected; a ratchet wheel engaging spring finger mounted on said rod; and a counter support and ratchet 60 wheel housing 2 enclosing the ratchet wheel 1 and forming a guide for one end of the rod 3.

The counter V is preferably attached, as shown in Figs. 1 and 2, to a supporting plate 2^b, which is preferably provided with a curved lip 2^e, as shown in Figs. 2 and 4, adapted to fit against one of the standards S, or other part, of the machine to which the attachment is secured; and may be fastened thereto by a bolt 4 as indicated in Figs. 1 and 2. The support 2^b may be of any desired shape, which will enable it to support the counter and be readily fastened to the machine with which the counter is to be 70 used.

As shown in Figs. 1, 2 and 3, the shaft V' of the counter is provided on one end, exterior to its casing, with a ratchet wheel 1 fixedly attached thereto in any desired manner, and preferably having ten teeth 1^a, the hub 1^b of the ratchet wheel spacing it from the adjacent end of the counter casing.

Enclosing the ratchet wheel 1 is a cylindrical housing 2, preferably closed at its 80 outer end by a head 2^o, said housing being preferably of the same exterior diameter as the counter casing, and being preferably rigidly attached to the plate 2^b as shown in Fig. 4.

Pivottally mounted on the inner face of plate 2^o within the housing 2, adjacent the top thereof is a pawl 2^f adapted to engage the teeth 1^a of ratchet wheel 1, and prevent backward movement of said ratchet wheel. 90 A suitable spring 2^g holds pawl 2^f yieldingly in engagement with the teeth of the ratchet wheel. In the sides of the housing 2 are opposite openings 2^c, 2^d, for the passage of an actuating rod 3, said openings being in line 100 at one side of the periphery of the ratchet wheel 1.

The actuating rod 3 may be of any suitable construction, and is preferably made of stout wire. It extends through the openings 2^c, 2^d, in the housing and its outer end is supported and guided in the opening 2^d.

The inner end of the rod is adapted to be attached to a movable part of the machine to which the counter is applied; which movable part should be a part that is operated 5 once for each operation of the machine that it is desired to count.

As illustrated in Fig. 1 the inner end of the rod 3 is engaged with the ribbon vibrator arm R of an "Elliott-Fisher" machine, and 10 the rod 3 will be reciprocated each time the bar R is operated.

Attached to the rod 3 is a spring member 3^b, the free end of which projects through the opening 2^c into the housing 2, and is 15 adapted to engage the teeth 1^a of the ratchet wheel when the rod 3 is moved outward. The finger 3^b is preferably formed of a narrow strip of spring metal, bent so that the free end thereof will normally tend to project 20 away from the adjacent part of bar 3. The other end of the spring finger is attached to the rod 3. Preferably the rod 3 has a flattened portion 3^a near the middle thereof, adapted to form a seat for the end of the 25 spring finger 3^b, which may be securely fastened to bar 3, parallel therewith by a screw 3^c. The finger 3^b may be adjusted on the rod by providing the finger with a slot 3^d for the passage of screw 3^c (Figs. 1 and 2), and 30 finger 3^b should be so adjusted that its free end will be in position to engage the teeth 1^a of the ratchet wheel 1, when the rod is retracted, as shown in Fig. 2.

The spring 3^b may be attached to rod 3 in 35 any suitable manner. As shown in Fig. 5 spring 3^b is attached to a collar 3^e which collar is adjustable on the rod 3 by a set screw 3^f.

Rod 3 may be connected to part R in any 40 suitable manner. As shown in Figs. 1-3 the inner part of rod 3 is bent inwardly as at 3^g, then bent sharply at right angles to the length of the rod as at 3^h, and then outwardly as at 3ⁱ, parallel with the length of 45 the rod 3, and part 3^j of rod 3 can be engaged with a hole R' in the arm R, and when the rod is in operative position (Fig. 1-3) the part 3^j will prevent disengagement of rod 3 from the arm R.

As shown in Fig. 5 the rod 3 may be fastened to arm R by means of a screw 3^k passing through a loop 3^l on the end of the rod 3.

The spring finger 3^b will turn the ratchet wheel when rod 3 is moved to the right, but 55 will not turn the ratchet wheel more than one tooth for each vibration of the ribbon arm of the machine, for when the spring 3^b has once forced the ratchet 1 to turn one 60 tenth of a revolution (there being ten teeth on the ratchet) the further outward movement of the spring finger 3^b disengages it from the ratchet wheel and the spring then bears against the teeth of the ratchet (see 65 Fig. 3) and will prevent turning of the

ratchet wheel in either direction, until the rod 3 is again returned to the position shown in Fig. 2, and the rod may even play back and forth, to a limited extent, while the spring bears against the teeth, as in Fig. 3 as 70 the spring rod cannot again be engaged with the ratchet, until after the rod is pulled back by the ribbon vibrator arm R of the machine to the position shown in Fig. 2, and another cycle of operations begun by the depression 75 of one of the keys of the machine.

The attachment may be placed in almost any desired position on a typewriter or Elliott-Fisher machine, and operatively connected therewith. The spring finger, as described, makes it impossible for the ratchet wheel to be moved more than one tooth for each stroke of the rod 3, by reason of the fact that once the ratchet has been turned a distance of one tooth the spring finger slides on 80 the outer edges of the teeth and cannot be ready for another stroke until the rod 3 has been withdrawn to its outermost position. 85

When applied to an Elliott-Fisher machine, or typewriter, each time the ribbon vibrator arm R is vibrated the ratchet wheel 1 will be rotated one tooth and when ten such vibrations have been made (there being 10 teeth on the ratchet wheel) the counter will register one unit. If the operator is 90 computing the cost of copying as at so much per unit registered by the counter, the number of units so typed will be shown by the counter when the work is completed, by subtracting the number shown on the counter 95 before the work is started, from the number appearing thereon when the work is completed. 100

The attachment may obviously be applied 105 to various machines having an arm or part that is reciprocated once for each operation of the machine to be registered.

What I claim is:

1. For a machine having a movable part 110 operated once for each operation of the machine that is to be counted, and having a counter having means for attaching the counter to the machine, and having a ratchet wheel on the counter shaft; a reciprocable spring member connected to the said movable part of the machine and adapted to engage said ratchet wheel and turn same one tooth when the member is moved in one direction and on further movement in the same direction to disengage the ratchet wheel and prevent further turning thereof until the spring member is returned to retracted position, substantially as described. 115

2. For a machine having a movable part 120 operated once for each operation of the machine that is to be counted, and having a counter, having means for attaching the counter to the machine, and having a ratchet wheel on the counter shaft; a reciprocable rod extending beside the ratchet wheel and 125

- connected to the said movable part of the machine; and a spring member on said rod adapted to engage said ratchet wheel and turn same one tooth when the rod is moved 5 in one direction, and means to prevent reverse turning of the ratchet wheel until the spring member has been returned to retracted position, substantially as described.
3. In mechanism as set forth in claim 2, 10 said spring finger being adjustably attached to and extending longitudinally of the rod and having its free end normally projecting away from the adjacent part of said rod, and adapted to disengage from said tooth 15 after having turned the ratchet wheel a distance equal to one tooth and to slide along the peripheries of the ratchet teeth to prevent turning of said ratchet wheel until the spring finger has been returned to retracted position.
4. For a machine having a movable part operated once for each operation of the machine that is to be counted; and having a counter, having means for attaching the 25 counter to the machine, and having a ratchet wheel on the counter shaft; a reciprocable rod extending beside the ratchet wheel and connected to the said movable part of the machine; and a spring member on said rod 30 adapted to engage said ratchet wheel and turn same one tooth when the rod is moved in one direction, and on further movement in the same direction to disengage the ratchet wheel and prevent further turning thereof 35 until the spring member has been returned to retracted position, substantially as described.
5. For a machine of the character specified, having a movable part operated once 40 for each operation of the machine that is to be counted, the combination with a counter, and having means for attaching the counter to the machine, and having a ratchet wheel on the counter shaft; a housing for said 45 ratchet; a reciprocable rod directly attached at one end to the movable part with the other end passing through said housing and supported thereby beside the ratchet wheel, means connecting the rod to the said movable part; a spring finger on said rod adapted 50 to engage said ratchet wheel and turn same one tooth when the rod is moved in one direction and on further movement to disengage the ratchet wheel and prevent turning thereof until the finger has been returned to normal retracted position; and a pawl adapted to engage said ratchet wheel 55 to prevent backward movement thereof.
6. For a machine having a movable part operated once for each operation of the 60 machine that is to be counted, and having a counter mounted thereon having a ratchet wheel on the counter shaft; a reciprocable rod extending beside the ratchet wheel and connected to the said movable part of the 65 machine; a spring member on said rod adapted to rotate said ratchet wheel a distance of one tooth when the rod is moved in one direction, said spring member being adjustably attached to and extending longitudinally of the rod and having its free end 70 normally projecting away from the adjacent part of said rod, and adapted to disengage from said ratchet tooth after having rotated the ratchet wheel one tooth and to 75 slide along the outer edges of adjacent teeth to prevent rotation of the ratchet wheel in either direction until the spring member has been retracted.
7. For a machine having a movable part 80 operated once for each operation of the machine that is to be counted, and having a counter mounted thereon having a ratchet wheel on the counter shaft; a housing for said ratchet; a reciprocable rod having one 85 end attached to the movable part of the machine and the other end supported by said housing and extending beside the ratchet wheel; a spring member on said rod adapted to rotate said ratchet in one direction; 90 said housing comprising a casing having one closed end, means for mounting the casing on the machine to enclose the ratchet wheel, said casing being provided with opposite openings disposed substantially tangent to 95 the ratchet wheel, one opening being adapted to receive and support the outer end of the reciprocable rod, and the other opening being adapted for the passage therethrough of the rod with the spring member mounted thereon.

In testimony that I claim the foregoing as my own, I affix my signature.

STEPHEN A. COUSE.
